UNITED STATES PATENT OFFICE.

WILLIAM C. BRUMDER, OF MILWAUKEE, WISCONSIN.

TYPE-WRITER.

1,198,322.

Specification of Letters Patent. Patented Sept. 12, 1916.

Application filed October 7, 1915. Serial No. 54,579.

To all whom it may concern:

Be it known that I, WILLIAM C. BRUMDER, a citizen of the United States, residing at Milwaukee, in the county of Milwaukee and 5 State of Wisconsin, have invented a certain new and useful Improvement in Type-Writers, of which the following is a full, clear, concise, and exact description, reference being had to the accompanying drawings, forming a part of this specification.

My invention relates to typewriters, and has for its object the provision of a type or other character writer of this character in which the operation may be controlled by 15 the selective operation of a very much smaller number of control elements than the ultimate number of letters or characters which the device may print or otherwise set up.

20 In the preferred form of my invention, I employ a plurality of character controlling elements whose selections in different combinations or in different order or in amount of movement controls the ultimate selection 25 of a given character in accordance therewith. In this application I show one specific form of such device constructed in accordance with my invention, and in this particular device I have five character 30 selecting bars which are all associated or placed in juxtaposition to a number of elements corresponding to the characters desired for selection. These character selecting bars are movable and by the selection 35 for movement of one or more of these character selecting bars any one of a great plurality of characters may be selected; even though as in the specific device herein illustrated each bar is designed to move but one 40 step. I will explain this specific form of carrying out my invention more in detail by referring to the accompanying drawings illustrating said specific embodiment, in which—

45 Figure 1 is a top plan view of a device constructed in accordance with my invention; Figs. 2, 3 and 4 are longitudinal sectional views respectively taken between various selecting bars; Figs. 5, 6, 7, 8 and 9 50 are side views respectively of the selecting bars; Fig. 10 is a bottom view showing the transversely mounted character elements; Fig. 11 shows one of the character elements in detail together with the circuit it con-

trols; Fig. 12 is a detail sectional view on 55 line *a*—*a* of Fig. 6, and Fig. 13 is a detail sectional view on line *b*—*b* of Fig. 7.

My invention contemplates the provision of a suitable base plate 1 upon which seven keys respectively 2, 3, 4, 5, 6, 7 and 8 are 60 pivotally mounted. These keys 2, 3, 4, 5 and 6 are respectfully pivotally associated with selecting bars 9, 10, 11, 12 and 13, which selecting bars as shown more clearly in Figs. 12 and 13 consist of a metallic strip 14 carrying an insulating rib 15, which insulating rib as shown more clearly in Figs. 2 to 9 has teeth, some of which teeth have metallic caps 16. These bars 9 to 13 slide horizontally over the base plate 1 in answer to the 65 movement of the buttons 2 to 6 inclusive. The movement of any button or key moves the corresponding bar one step. Now by the selection of one or more bars it is possible to determine the selection of any one 70 of a plurality of characters, and this selection is due to the selective placing of the metallic cap 16 upon some of the teeth, whereas other teeth, designated by 16^a, are merely extensions of the insulating strip 16. 75 These bars coöperate with type elements 17 to 44 inclusive, each type element having a peculiar construction to coöperate with the teeth of the bars, and each element when properly controlled serving to cause the actuation of the character corresponding to that element. This will be more readily understood by an inspection of Fig. 11 where the element 42 is shown. This element in the particular construction herein disclosed 80 consists of a strip 45 of insulating material having at its extremities conducting pins 46 and 47 by virtue of which it is pivotally mounted in side frames 48, 49, (referring to Fig. 1). The side frame 48 is metallic so 85 that all of the pins 46 contact with it and one binding post 50 is used to extend the circuit from this side frame 48 by means of conductor 51 to a battery 52. The other pins 47 are insulatingly mounted in the 90 side frame 49, but are connected each to each to binding posts 53, from which binding posts conductors 54 may extend to relays 55, there being one relay for each type element, and each relay 55 controlling a 95 particular type lever 56, which type lever may actuate suitable type or other character as in an ordinary typewriter. The other

terminal of the battery 52 is then of course connected by means of conductor 57 with the other terminal of the relay 55, the conductor 57 being a common conductor, but conductor 54 being one of a plurality of individual conductors, one leading from each type element such as 18. These type elements 18 are hinged as stated and which have at various points on their lowermost 5 extremity openings which are faced on the sides by contact strips 58, 58. These contact strips, referring to Fig. 11, are serially included in a circuit extending from the pin 46 to the pin 47. It will be seen from this 10 that no circuit can be completed through the type element 42 unless both of the contact devices 58 in this element are connected together. There being five bars, I may say that these are shown in the side view in 15 Figs. 5 to 9 inclusive and are also respectively denominated by the Roman numerals I, II, III, IV, and V.

It will be seen by an inspection of Fig. 10 that the various elements 17 to 44 inclusive are provided with metallically faced 20 openings 58 which are in definite rows, and these rows are also designated by the Roman numerals I, II, III, IV, and V, so as to show which of the bars 9 to 13 coöperates 25 with the particular row of openings 58 of these various type elements 17 to 44 inclusive. An inspection of Fig. 10 will show that so far as the element 42 is concerned, it is necessary to move the bars corresponding 30 to the Roman numerals III and IV one step in order to close the circuit through this element 42. That corresponds to the bars 11 and 12. Thus a movement of the keys 4 and 5 to move their respective bars 35 one step would cause the closure of the circuit through the type bar 42. The functions of the teeth 16 are to tilt various of the elements 18 to 44 inclusive out of their vertical position by having these teeth engage 40 the unbroken lower face of said elements. It may be stated that these insulating teeth 16 can pass through the openings 58 without touching or moving the bars. Thus if we refer for instance to Fig. 2 in 45 which the bar 9 is shown in its normal position, and all of the elements are shown in their vertical position, and then assume the alternative position of Fig. 3, in which the bar 9 has been moved one space to the right, then it will be seen that this bar 9 (comparing 50 also column 1 of Figs. 5 and 10), has beginning at the left sixteen conducting teeth 16, and these may enter all of the metallically faced openings of the sixteen first 55 type elements and consequently completing the circuits therethrough. The remaining teeth of bar 9 however are required, and under these conditions would push the remaining type elements 33 to 44 inclusive out of line as shown in Fig. 3. This movement

of one step of the bar 9 however completes the circuit only through the element 17 as it will be apparent from an inspection of Fig. 10 that the remaining elements 19 to 32 inclusive require the closure of more than one 70 metallically faced opening 58. The element 33 needs closure of but one metallically faced opening 58, but that would be due to a movement of the bar 10.

The combinations have been so worked 75 out that but one of the elements 18 to 44 inclusive has its complete circuit closed with any given combination of the bars 9 to 13. In those cases where there might be interference, the insulating teeth push those of 80 the elements 18 to 44 inclusive which might interfere out of the path as shown for instance in Figs. 3 and 4 so that there will not be a double type actuation. It is to be understood that the metallically headed 85 teeth 16 may enter into the metallically faced openings 58 without moving them substantially out of their vertical alinement, and this of course can be done by a slight inclination of the faces or in any other suitable way which would permit positive withdrawal of these teeth without dragging these elements along out of their neutral position; but contacts of course could be used if desired. It will be understood of course 90 also that the arrangement can be such that the teeth 16 and 16^a normally occupy positions within the openings 58 or others to be provided so that all circuits are normally closed except those which are opened by a 95 combinational movement of the elements, which is just the reverse of what is herein illustrated.

There are two additional keys 7 and 8 as shown in Fig. 1 and these are supposed to 100 control additional circuits that may extend from the device of Fig. 1 to additional relays such as 55 which can be used for upper or lower case work so that three characters may be utilized upon each type lever 56 in 105 accordance with ordinary typewriter principles. Assuming that but twenty-six of the type elements are needed for the list, then the additional ones provided can be utilized for carriage return, spacing, and 110 line adjustment purposes. It will of course be understood that further combinations can be secured by a change in the sequence of 115 operation of the bars so that the order in which they are selected controls.

From what has been described the nature 120 of my invention will be readily clear to those skilled in the art.

Having however thus described one specific form which my invention may take, 125 what I claim as new and desire to secure by Letters Patent is:

1. In a device of the character described the combination with a plurality of individual circuit controlling elements, each 130

element corresponding to a given character, of a plurality of means for selectively co-acting with said elements to operatively select any desired element to effect an operative control of its associated circuit, and means for selectively actuating said means.

2. In a device of the character described the combination with a plurality of individual circuit controlling elements, each element corresponding to a given character, of a plurality of control devices each co-operating with each of said elements, means whereby said devices interlock with said elements, and means controlled by the relative selective movements of said control devices relative to said elements to select for operative selection any desired element aforesaid to effect an operative control of its associated circuit.

3. In a device of the character described the combination with a plurality of individual circuit controlling elements, each element corresponding to a given character, of a plurality of control devices each co-operating with each of said elements, and means controlled by the relative selective movements of said control devices relative to said elements to select for operative selection any desired element aforesaid to effect an operative control of its associated circuit.

4. In a device of the character described the combination with a plurality of individual circuit controlling elements, each element corresponding to a given character, means associated with each of said elements adapted when operatively controlled to operatively place the corresponding element into condition for character controlling purposes, and a plurality of control devices each associated with each of said elements having interlocking mechanism to selectively control said elements to effect an operative control of its associated circuit.

5. In a device of the character described the combination with a plurality of individual circuit controlling elements, each element corresponding to a given character, of a plurality of control devices each co-operating with each of said elements, and means interposed between said elements and devices whereby any one of said elements is selected for operative actuation in accordance with the selected movements of said control devices to effect an operative control of its associated circuit.

6. In a device of the character described the combination with a plurality of individual signal circuit controlling elements, each element corresponding to a given character, of a plurality of control devices each co-operating with each of said elements, and means interposed between said elements and devices whereby any one of said elements is selected for operative actuation in accordance with the selected movements of said

control devices to effect an operative control of its associated circuit.

7. In a device of the character described the combination with a plurality of individual signal circuit controlling elements, each element corresponding to a given character, each of said elements having individual means controllable to select the corresponding element for operative selection, of a plurality of control devices each co-operating with each of said elements, and selectively co-operating with said means to select the desired element in accordance with the selective movements of said devices to effect an operative control of its associated circuit.

8. In a device of the character described, the combination with a plurality of individual signal circuit controlling elements, each element corresponding to a given character, each of said elements having individual means controllable to select the corresponding element for operative selection, said means including contact fingers, of a plurality of control devices each co-operating with each of said elements, and selectively co-operating with said means to select the desired element in accordance with the selective movements of said devices to effect an operative control of its associated circuit.

9. In a device of the character described the combination with a plurality of parallelly arranged individual signal circuit controlling elements, each element corresponding to a given character, of control devices movable transversely to said elements, and interlocking mechanism interposed between said elements and said devices, whereby selective movements of said devices select corresponding elements for control purposes to effect an operative control of their associated circuits.

10. In a device of the character described the combination with a plurality of individual signal circuit controlling elements, each element corresponding to a given character, each of said elements having individual means controllable to select the corresponding element for operative selection, of a plurality of control devices each co-operating with each of said elements and having means to select any desired element for actuation in accordance with the selected grouping of said control devices to effect an operative control of its associated circuit.

11. In a device of the character described the combination with a plurality of individual signal circuit controlling elements, each element corresponding to a given character, each of said elements having individual means controllable to select the corresponding element for operative selection, of a plurality of control devices each co-operating with each of said elements, and means for operating said devices in groups

to thereby select any desired element for actuation to effect an operative control of its associated circuit.

12. A device of the character described comprising a selective signal controlling apparatus having a plurality of character elements, each adapted to control an individual electric circuit, a plurality of selecting elements, and means interposed between said elements to cause the selective actuation of said character elements in accordance with

the group actuation of said selecting elements to thereby effect operative control of their associated electric circuits.

In witness whereof, I hereunto subscribe 15 my name this 25th day of September, A. D. 1915.

WILLIAM C. BRUMDER.

Witnesses:
